(57) **CLAIM**

The ornamental design for a magnetic fly patch, as shown and described.

DESCRIPTION

FIG. 1 is a front perspective view of a magnetic fly patch showing the new design.

FIG. 2 is a rear perspective view of a magnetic fly patch showing the new design.

FIG. 3 is top view of a magnetic fly patch showing the new design.

FIG. 4 is a front view of a magnetic fly patch showing the new design.

FIG. 5 is a first side view of a magnetic fly patch showing the new design.

FIG. 6 is a rear view of a magnetic fly patch showing the new design.

FIG. 7 is a second side view of a magnetic fly patch showing the new design.

FIG. 8 is a bottom view of a magnetic fly patch showing the new design.

FIG. 9 is a front perspective view of a magnetic fly patch showing the new design with the rear plate detached from the main body; and,

FIG. 10 is a rear perspective view of a magnetic fly patch showing the new design with the rear plate detached from the main body.
